ENCLOSURE FOR A FLUSH VALVE

Charles William Sloan, Don Mills, Ontario, Canada,
assignor to Josam Products Limited, Toronto,
Ontario, Canada, a corporation of Ontario

Filed Feb. 19, 1964, Ser. No. 78,698

Term of patent 14 years

The elements shown in broken lines in FIGS. 1, 2 and 3 are included for illustrative purposes only.

I claim:

The ornamental design for an enclosure for a flush valve, as shown and described.
